Attorney

UNITED STATES PATENT OFFICE.

THOMAS C. HUTCHINSON, OF DULUTH, MINNESOTA.

GRAIN-DOOR REMOVER.

Application filed October 22, 1923. Serial No. 669,911.

To all whom it may concern:

Be it known that I, THOMAS C. HUTCHINSON, a citizen of the United States, residing at Duluth, in the county of St. Louis 5 and State of Minnesota, have invented certain new and useful Improvements in Grain-Door Removers, of which the following is a specification, reference being had therein to the accompanying drawing.

10 This invention relates to grain door removers and has special reference to that class of grain door used temporarily in railroad cars.

The principal object of the invention is 15 to provide as simple means as possible for the ready and indestructible removal of such doors.

Other objects and advantages of the invention will appear in the further description 20 thereof.

Referring now to the accompanying drawing forming part of this application, and in which like reference characters indicate like parts:

25 Figure 1 is a transverse sectional view through a grain car, located in position within an elevator for discharging its contents; and

Figure 2 is an enlarged broken perspective view of the principal element embodying the invention.

To those versed in the art, the difficulties encountered in removing the grain door of a car are well known, and how that various means for assisting in the forcing inwardly of the body or sections of a grain door for the purpose of discharging the contents thereof have been heretofore resorted to, and my present invention relates 40 to the use of a simple pushing beam or ram, manipulated in the most convenient manner possible.

In illustrating the embodiment of the invention, I have shown the floor of an elevator at 1, upon which the car tracks 2 are mounted, they being spaced apart, and in some instances having a raised platform 3 therebetween, through which pass vertically disposed elevator legs as indicated at 4; 45 though this is but one form of discharging means for railroad cars.

However, in this instance, I have illustrated a portion of a box car at 5, the same being loaded with grain and provided with 50 a sectional grain door, indicated at 6, the same usually being of wooden construction

and nailed to the inner side of the door post 7 of the car, so that when it is desired to discharge the contents of the car, it becomes necessary to force or chop away the grain door, the latter method frequently being resorted to in respect principally to the lower portion of the door. It is found in practice that if the sections of the door may be forced inwardly and upwardly 60 much more desirable results are obtained and the destruction of the door avoided, and to accomplish this I provide a comparatively short pushing beam 8, preferably of wood, having pivotally installed at 65 one end a roller 9 and in the opposite end a pivotally mounted door engaging shoe 10. For cooperative action with this pushing beam I provide uprights or stanchions 11 70 preferably of angle iron, rigidly attached 75 either to the corners of the elevator structures 4, or rigidly supported in any other manner desired. These angles are installed so as to face the track, and are a distance from the grain door of a car thereon usually 80 8 or 10 inches less than the overall length of the beam or ram 8. The ram is provided with a lifting eye 12 installed adjacent the roller end thereof, the same being 85 for the reception of the hook 13 on the pulling line 14, which depends from a suitable sheave 15 installed overhead, and power of any description may be applied to said line. Thus when the hook is applied to the eye 12, an upward draft upon the line will raise 90 the innermost end of the beam 8, and, if the shoe 10 on the opposite end of the beam has been placed against the grain door of the car, it is obvious that the same will be forced inwardly and upwardly, effectively 95 dislodging the same with the least effort possible on the part of the man engaged in such work.

It is well known that in such installations, there is ample power available in the form 100 of pulling lines, and trip ropes are employed for stopping and starting same, so that this feature does not form part of my present invention. Furthermore it is apparent that one or more stanchions 11 may be installed 105 to accommodate the varied positions of the cars as the ram 8 may be readily placed into one or the other as circumstances may require, and various other modifications of the specific structure here shown may be 110 resorted to without departing from the spirit of the invention.

Having thus described my invention, what I claim and desire to secure by Letters Patent, is:

1. A grain car door opening device comprising in combination an upright fixed stanchion spaced from the grain door of a car and independently thereof, a portable beam, having a door engaging shoe pivotally mounted in one end thereof and 5 a stanchion roller at the other end for installation intermediate of the door and the stanchion, and a line suspended from overhead for vertically raising the stanchion end of the beam for the purpose described.
- 10 2. A car door removing device of the character described comprising a V-shaped upright permanent stanchion spaced from

the door of the car and a portable beam for installation between the upright and the door of the car, said beam having a 20 door engaging shoe pivotally mounted in one end thereof and a roller, for engagement within the V-shaped channel in the stanchion, in the other end thereof, and a hoisting rope suspended from above the 25 stanchion end of the beam for raising same for the purpose described.

In testimony whereof I hereunto affix my signature in the presence of two witnesses.

THOMAS C. HUTCHINSON.
